(57) **CLAIM**

The ornamental design for a portable electric generator, as shown and described.

DESCRIPTION

FIG. 1 is a front perspective view of a portable electric generator showing a first embodiment of my design.

FIG. 2 is a front elevational view of the portable electric generator of FIG. 1.

FIG. 3 is a rear elevational view of the portable electric generator of FIG. 1.

FIG. 4 is a left side elevational view of the portable electric generator of FIG. 1.

FIG. 5 is a right side elevational view of the portable electric generator of FIG. 1.

FIG. 6 is a top plan view of the portable electric generator of FIG. 1.

FIG. 7 is a bottom plan view of the portable electric generator of FIG. 1.

FIG. 8 is a front perspective view of a portable electric generator showing a second embodiment of my new design.

FIG. 9 is a front elevational view of the portable electric generator of FIG. 8.

FIG. 10 is a rear elevational view of the portable electric generator of FIG. 8.

FIG. 11 is a left side elevational view of the portable electric generator of FIG. 8.

FIG. 12 is a right side elevational view of the portable electric generator of FIG. 8.

FIG. 13 is a top plan view of the portable electric generator of FIG. 8; and,

FIG. 14 is a bottom plan view of the portable electric generator of FIG. 8.

The broken lines and the areas within the broken lines are for illustrative purposes only and form no part of the claimed design.
